UNITED STATES PATENT OFFICE.

JAMES J. NICHOLSON, OF DETROIT, MICHIGAN.

PROPELLER.

Application filed February 21, 1925. Serial No. 10,743.

To all whom it may concern:

Be it known that I, JAMES J. NICHOLSON, a citizen of Denmark, residing in Detroit, in the county of Wayne and State of Michigan, 5 have invented certain new and useful Improvements in Propellers, of which the following is a specification.

This invention relates to improvements in propellers as used in the propulsion of vehicles and more particularly to such as are 10 adapted for use either wholly or partially in the air, including helicopters, aeroplanes, sea and ice planes, flying machines and dirigibles of like character.

15 The broad general nature of the invention may be characterized by the provision of means for creating artificial resistance to the blades of a screw propeller or other propulsive means employed.

20 It is therefore an object of the invention to provide means for accomplishing this purpose in a practical and efficient manner, utilizing, whenever possible, the exhaust of the motor by which the propeller is actuated.

25 A further feature is in the provision of propeller blades having a transversely ridged or striated surface against which is projected streams of air, steam, gases, water or the like in such manner as to oppose the direction of rotation of the blades and deliver the streams outward in a substantially tangential direction thereto.

30 Another aim is to provide a blade structure that is essentially strong, light in weight and relatively inexpensive to construct or apply.

35 These several features are accomplished by the novel construction, combination and arrangement of parts hereinafter described and shown in the accompanying drawings forming a material part of this disclosure, and in which:—

40 Figure 1 is a front elevational view of a conventional type of propeller made in accordance with the invention.

Figure 2 is a side or edge elevational view of the same, partially in section.

45 Figure 3 is a view similar to Figure 1 but showing a modification in construction.

Figure 4 is a side elevational view of the propeller shown in Figure 3.

50 Figure 5 is an enlarged transverse sectional view taken on line 5—5 of Figure 3.

55 Referring more in detail to the drawings, the numeral 10 designates a hollow cylin-

drical shaft, closed at its outer end 11 to prevent escape of air or the like in the bore 12 of the shaft.

It is to be understood that the shaft is 60 revolvably mounted in bearings carried on the vehicle, the shaft driven by a motor in the usual manner and being in communication with a supply of compressed air, gases or steam as the exhaust of the motor, or water 65 supplied under pressure from a tank if the propeller be used for aquatic purposes.

Fixed on the outer end of the shaft are inner and outer flanges 13 and 14 respectively having rigidly engaged between them 70 a hub 15 from which extend opposed blades generally denoted by the numeral 16.

Each blade consists of plate 17 gradually decreasing in thickness from the rounded rear edge 18 to the relatively thin advance 75 edge 19 which is twisted at an angle of approximately fifteen degrees from the normal plane of the blade.

The inner surface 20 of the blade is plane and level and on the outer surface are a 80 series of spaced, raised transverse ridges or serrations 21 having angular faces 22 inclining towards the adjacent ridge, the slant of each face or step 22 being inward towards the blade from the hub 16 to the widened 85 and rounded outer end 23.

As shown in Figures 1 and 2 a thin tube 24 is fixed on the advance edge of the propeller, extending from the inner face of this abutment 25 of the end 23, to the hub 15, 90 which it enters at an angle, as at 26, to extend substantially through the center and communicate with the interior of the tubular shaft 10.

Air or the like, under compression, is 95 blown outward through a series of perforations 27 to impinge against the surfaces 22 and discharge into the atmosphere at a tangent to the rotation of the blade, the current of compressed air or the like being materially guided and controlled by the steps 21 in a straight path across the propeller, very materially opposing the resistance of the atmosphere against the propeller blade so that the speed need not be maintained at 105 so high a rate as is otherwise required.

In the form illustrated in Figures 3 to 5, a substantially triangular tube 28 extends from the abutment 25 at the end 23 and is bent as at 29 to pass through the hub 14 110 and communicates with the hollow shaft 10 in the manner previously described.

Air is forced outwardly through slits or elongated openings 30 to impinge on the transversely bevelled surfaces 22 which are also bevelled outwardly to blend into the thickened rounded edge 18.

It is to be noted, in the form shown, that the tube 28 forms the advancing edge of the blade, presenting a relatively narrow area for that purpose, and it will be understood 10 that all blades are similarly provided with resistance devices of the kind described.

Although I have described my improvements with considerable detail and with respect to certain particular forms of my invention, I do not desire to be limited to such details since many changes and modifications may well be made without departing from the spirit and scope of my invention 15 in its broadest aspect.

Having thus described my invention, what I claim as new and desire to secure by Letters Patent, is:—

1. A propeller comprising a hub having a pair of opposed radiating blades, transverse 25 ridges on the outer flat surfaces of the blades, said ridges having sharply angled abutments directed towards the hub and bevelled surfaces inclined towards the entering edges of the blades, a tube adjacent the entering edge

of each blade, a hollow shaft on which the hub is fixedly engaged, said hollow shaft being in communication with a supply of compressed air or the like, said tubes passing through the hub to communicate with said shaft and containing openings adapted to 30 deliver an air blast upon the bevelled surfaces of the blades in a direction opposite that of rotation of the blades.

2. A propeller comprising a hub having two diametrically opposed flat blades, transverse ridges on the outer flat surfaces of the blades, said ridges having sharply angled abutments extending squarely across the blades and bevelled surfaces inclined inward towards the hub and towards the 45 entering edges of the blades, a hollow shaft for said hub, said shaft being in communication with a supply of compressed air or gases, a triangular tube disposed on the advance edge of each blade with its apex of 50 the angle of the tube outward, and slits in the base elements of the tubes directed to impinge on each of the bevelled surfaces of the blades adjacent the abutments thereof.

In testimony whereof I have signed my name to this application.

JAMES J. NICHOLSON.
